UNITED STATES PATENT OFFICE.

LATHAM H. BRIGHTMAN, OF COLUMBUS, OHIO.

AUTOMATIC CUT-OFF MACHINE.

1,226,303.

Specification of Letters Patent. Patented May 15, 1917.

Application filed February 7, 1916. Serial No. 76,814.

To all whom it may concern:

Be it known that I, LATHAM H. BRIGHTMAN, a citizen of the United States, residing at Columbus, in the county of Franklin and State of Ohio, have invented certain new and useful Improvements in Automatic Cut-Off Machines, of which the following is a specification.

This invention relates to automatic cut-off machines to be used essentially in cutting short sections of rods or shafting. There are a great number of instances in which my machine may be used to advantage, one of them being particularly in the use of roller bearings wherein short sections of steel rods are severed to uniform length.

The main object of my invention resides in a type of structure wherein the stop against which the steel rod or shafting is fed, is receded from its original position to permit the free dropping of the severed end after the cut-off tool has completed the severance. I have found that where the stop is rigidly held in its original position, the severed end of the rod is apt to assume an unnatural position at about the time the severance is completed and in so doing places an unnatural strain upon the machine as a whole and in a great many instances, either causes the breaking of the cut-off tool itself or the stop. This follows since the amount of material cut away is only equal to the width of the cut-off tool itself and consequently the severed end tends to stop its rotation when the severance is completed, while the remaining stock bar continues its rotation and in this manner the so-called wedging action may readily take place.

A further object of my invention is the feed mechanism used for forcing the stock bar into engagement with the stop above referred to, after the previous end of this stock bar has been severed and the cut-off tool withdrawn from its operative position. This feed mechanism comprises essentially a roll structure positively driven in such direction so that when it is brought into engagement with the stock bar itself, after the stock bar has been temporarily released by the rotating chuck, the action of the roll structure is such as to cause a forward feed of this stock bar into engagement with the stop to determine the next length of section to be severed.

The preferred embodiment of my inven-

tion is shown in the accompanying sheets of drawings, in which similar characters of reference designate corresponding parts, and in which:

Figure 1 is a longitudinal vertical section 60 of the assembled machine showing my improvements incorporated therein,

Fig. 2 is a top plan view of the structure shown in Fig. 1,

Fig. 3 is a bottom plan looking up, of a 65 portion of the structure shown in Fig. 1 as represented by the line 3-3 of Fig. 1,

Fig. 4 is a view in side elevation of the feed mechanism for feeding the stock bar forward,

Fig. 5 is a top plan view of the structure shown in Fig. 4,

Fig. 6 is a view in perspective of a bushing forming a portion of the feed mechanism,

Fig. 7 is a partial plan view of the stop mechanism showing the structure by which it is regulated and its association with the mechanism for controlling the cut-off tools,

Fig. 8 is a side elevation of a portion of 80 the structure shown to the extreme right of Fig. 7,

Fig. 9 is a longitudinal section taken through the rotatable chuck,

Fig. 10 is a section taken on line 10-10 85 of Fig. 9,

Fig. 11 is a view in perspective of a clamp ring forming a portion of the rotatable chuck, and,

Fig. 12 is a section taken on line 12-12 90 of Fig. 9.

In these several views, the main frame or supporting framework of the structure is designated in its entirety by the reference numeral 1. The upper portion of this general framework carries a pair of bearing supports designated 2 and 3, in which the rotatable chuck shown in detail in Figs. 9 to 12 inclusive, is rotatably journaled, it being the purpose of this chuck to intermittently grasp the stock bar 4 to rigidly grip the same to cause its rotation at the same rotative speed as the chuck itself. Referring to Figs. 9 to 12 inclusive, it will be noted that the chuck comprises an outer 105 sleeve 5 on which the pulleys 6 and 7 are rigidly mounted.

This outer sleeve is threaded as is shown at 8 to accommodate the lock nuts shown at 9, whereby the sleeve itself is held against 110

longitudinal movement within the bearing 2, since these lock nuts coöperate with the enlarged portion 10 of the sleeve. The rear end of the sleeve is also threaded as is shown at 11, on to which portion the collar 12 is secured and this collar is then held in position by means of the lock nuts shown at 13. The collar 12 pivotally supports a pair of oppositely disposed dogs 14 and the short arms of these dogs engage an inner sleeve shown at 15. This inner sleeve is of a size to accommodate various sizes of stock bars and at its forward end it engages the clamp ring 16 shown in detail in Fig. 11. This clamp ring is provided with a number of slits 17 and an enlarged flaring head 18 which head is designed to coöperate with a complementally inclined wearing member 19 located within the enlarged portion 10 of the outer sleeve. The slits 17 are provided to give a certain degree of resiliency to the clamp ring and it will be apparent that should the inner sleeve 15 be forced toward the right, the flared head 18 will come into wedging engagement with the inclined wearing member 19, whereby the sectional bushing 20 located within the enlarged head 18 will be wedged into gripping relation with the stock bar. The dogs 14 are actuated by means of the cone shown at 21, as being slidably mounted on the outer sleeve and as actuated by means of a pair of levers 22 pivoted intermediate their ends, as shown at 23, to ears 24 projecting from the side of the bearing portion 3. The upper ends of the levers 22 are thus provided with pins 25 designed to slide in the grooved portion 26 of the cone 21.

As has been related, the structure of the machine is such that the chuck intermittently grasps and releases the stock bar 4 by the corresponding movement of the cone 21 upon the outer sleeve. At the time that the stock bar is released, the feed mechanism shown in detail in Figs. 4 and 5 comes into play to force the stock bar forward to bring its end into engagement with the stop shown at the right of Fig. 1. Also, the arrangement and timing of the machine is such that the stock bar is not released until the end of this bar previously fed forward, has been completely severed by the cut-off tools to be presently described. This feed mechanism comprises a pair of levers 27 oppositely disposed to each other to lie on opposite sides of the stock bar 4 and pivoted intermediate their ends upon shafts 28 and 29, which shafts are rotatably supported in a bearing bracket 30 carried by the main framework of the machine. One end of each of these levers is formed with a bearing portion 31 in which shafts 32 and 33 are located and on one end of each of these shafts there is rigidly mounted

a grooved roller shown at 34. The structure is such that these rollers are positively rotated and when the stock bar is released by the chuck, these rollers are brought into engagement with the stock bar and because of their rotation, feed the stock bar forward. The manner of rotating the rollers 34 is as follows: The rotatable chuck is provided with a gear 35 which meshes with a pinion 36 mounted on a counter shaft 37, which shaft also carries a gear 38 at its opposite end. This latter gear 38 in turn meshes with a complemental pinion 39 located on the counter shaft 40 and the opposite end of this shaft 40 is provided with a spiral gear 41 which meshes with a spiral gear 42 located on a shaft 43. This shaft 43 is then provided with a worm 44 which drives a worm wheel 45 located on a cam shaft 46 to be presently referred to. In addition, the shaft 43 is provided with a gear 47 which forms a portion of the train of gearing shown in Fig. 4 for driving the rollers. This gear 47 in turn drives a gear 48 located on a shaft 49 and this latter drives a gear 50 located on the shaft 29 already referred to. The gear 50 then in turn drives the gear 51 located on the roller shaft 33 and also the gear 52 located on the shaft 28. This latter gear 52 is also in engagement with the gear 53 which is rigidly mounted on the other roller shaft 32. Because the levers 27 are pivoted about the shafts 28 and 29, these levers may be moved and the gears 51 and 53 always maintained in mesh with their complemental gears 50 and 52 and because the gears 50 and 52 mesh with each other, the roll shafts 32 and 33 will rotate in opposite directions with respect to each other. The rear end of each of the levers 27 is connected to a carriage 54 by means of a link connection 55 adjustable by means of the nuts 56, the link itself being a threaded bolt threaded into the pivoted blocks 57. This carriage 54 is in turn slidably mounted on stub shafts 58, which latter project from and are rigidly supported by the bracket 30 already referred to.

The manner of bringing these rolls 34 into engagement with the stock bar is as follows: To the carriage 54 there is rigidly secured a tie rod 59 which is adjustable as to length by means of the structure shown at 60 and which at its opposite end is connected with one of the levers 22, as shown at 61, used to actuate the cone 21, which latter releases its grip on the stock bar. Thus, it will be apparent that as the cone 21 is moved toward the right, as indicated in Figs. 1 and 9, the grip on the stock bar is released and at the same time the tie rod 59 is moved to the right to cause a similar movement of the carriage 54. Because of the link connections 55 with the levers 27, the grooved rolls

34 are brought into contact with the stock bar and inasmuch as these rolls are continuously rotating, the stock bar will be fed in a forward direction. From this description, 5 it will be apparent that it is impossible to bring these rolls into contacting engagement with the stock bar before it has been released by the rotatable chuck.

In order to prevent the stock bar from 10 wabbling as the rolls 34 engage it, I have provided the bearing bracket 30 with an extension 30^a in which the bushing 30^b shown in Fig. 6, is adapted to fit. The internal bore of this bushing may be varied to accommodate various sizes of stock bars and the extension 30^a is itself so constructed as to be in alinement with the normal position of the stock bar as it is fed in. In this manner, 15 the stock bar is actuated before it engages 20 the rolls 34 and so prevented from wabbling at that point.

The manner of actuating the levers 22 will now be described: The lower ends of 25 these levers 22 are adjustably connected to a slide block 62 slidably mounted in the under portion of the bed plate through the medium of an adjustable link shown at 63. This slide block carries a roller 64 which operates in a groove 65 formed in a cam 66 30 which cam is located on the shaft 46 already referred to. Thus, the continuous rotation of the shaft 46 through its connection effected by the worm wheel 46, will cause the 35 operation of both the rotatable chuck and the in-feed mechanism.

The stop against which the stock bar is fed and its manner of operation, will now be described: This stop comprises a support 67 adjustably mounted on a rod 68 by 40 means of the bolts shown at 69. This rod is itself slidably mounted in a pair of brackets designated 70 and shown as being bolted to the main framework in any desired manner. The rear end of the slide rod 68 45 is so formed as to be pivotally attached as shown at 71 to a link 72 which is in turn pivotally connected to a crank arm 73 rigidly mounted on a shaft 74. This shaft 74 is suitably journaled in a bracket 75 supported from the main framework and carries at its opposite side a lever arm 76 and this latter lever arm is connected by means 50 of a universal connection shown at 77 to a pull rod 78. This pull rod is then in turn pivoted by means of a universal connection shown at 79 to one end of a bell crank 80, which bell crank is rigidly connected with a shaft 81. This shaft 81 is rotatably journaled in an ear 82 forming a portion of the 55 main framework and is also rigidly connected with a lever arm shown at 83. Now referring again to the cam shaft 46, it will be noted that this shaft also carries a cam 84 arranged to coöperate with a roller 85. 60 This latter roller is mounted on a bell crank

86 which is in turn pivotally supported from a bracket 87 from the main framework, as shown at 88. The short arm of the bell crank 86 is provided with a slot 89 and in this slot one end of a link 90 is rigidly 70 secured as is shown at 91. The opposite end of this link 90 is pivotally connected as shown at 92 with a tie rod 93. Referring particularly to Fig. 7, it will be noted that this tie rod is pivotally connected at 94 with 75 the lever arm 83 and the opposite end of this tie rod, referring now to Fig. 3, is pivotally connected as shown at 95 to a lever 96 pivoted intermediate its ends as shown at 97 to a bracket arm projecting from the 80 main framework. The opposite end of this lever 96 is then operatively connected to the cut-off tool support 98 by means of the link shown at 99 and consequently the movement of the cut-off tool supported in this 85 cut-off tool support 98 is governed by the pivotal movement of the lever 96. As shown in Fig. 7, the bell crank 80 rigidly mounted on the shaft 81, has one arm operatively connected with the other cut-off tool support 100 by means of a link connection 101 and consequently the movement of the cut-off tool supported in its cut-off tool support, is governed by the movement of the bell crank 80. However, the movements of 90 both tool supports are governed by the cam 84 as will now be related. Rotative movement of this cam 84 causes a movement of the bell crank 86 and this movement is in turn transmitted to the tie rod 93 by means 95 of the link connection 90. The tie rod 93 moves the lever 96 to in turn properly feed the tool support 98 and also moves the bell crank 80 through the medium of the lever connection 83, inasmuch as the tool support 100 is connected by the link 101 to the bell crank 80. Reference to Fig. 7 will also show that as the tool supports 98 and 100 are moved toward the stock bar, the right hand end of the bell crank 80 is moved toward the right. This motion is transferred by means of the connection 78 to the lever 76 and this lever then operates the shaft 74, which latter controls the movement of the crank 73 to withdraw the slide bar 68 105 through the medium of the link connection 72. Inasmuch as the stop support is rigidly mounted on the slide bar 68, this stop support will then be withdrawn from its engagement with the end of the stock bar as 110 the cut-off tools are fed into the stock bar itself.

This stop is also constructed to adjust the lengths of stock severed independently of the bolts 69. This construction comprises 125 the threaded rod 102 fitted within the upper portion of the stop support 67 and is held in any adjusted position by means of the nuts 103. Thus, by loosening one nut and tightening the other, the threaded rod 102 130

may be moved to the desired position and in this manner very minute adjustments may be effected.

From the foregoing description, taken in connection with the accompanying sheets of drawings, it will be apparent that I have provided a mechanism which will prevent the breaking of the cut-off tools to a marked extent. This I accomplish by gradually withdrawing the stop from its engagement with the end of a stock bar, after the stock bar has been fed forward its required or predetermined length and before the severance of the end of this stock bar has been completed. Further, particularly novel means have been provided for feeding the stock bar forward into engagement with the stock.

What I claim, is:

- 20 1. A machine of the class described comprising a chuck to hold the metal stock bar, means for feeding the stock bar through said chuck, a stop against which the end of said stock bar is to abut, means for feeding said tool into and away from said stock bar, and means for withdrawing said stop in a longitudinal direction from its engaging contact with the end of said stock bar during the time the cut-off tool is being fed into 30 the bar.
- 25 2. A machine of the class described comprising a main frame, a chuck to hold the metal stock bar, means for feeding the stock bar through said chuck, a cut-off tool, means for feeding said tool into and away from said stock bar, a slide bar slidably supported in said framework, a stop support adjustably mounted on said slide bar, a stop member adjustably supported in said member 35 against which the end of the stock bar is fed, and means connected to said slide bar to move it in a longitudinal direction to withdraw said stop member from engagement with the end of said stock bar during 40 the time said cut-off tool is fed into the bar, said separation being complete before the bar end is severed.
- 30 3. A machine of the class described comprising a chuck to hold the metal stock bar, means for feeding the stock bar through said chuck, a stop against which the end of the stock bar is fed, a cut-off tool, means for feeding said tool into and away from said stock bar, and means operable after the 45 cut-off tool has started the cutting action for withdrawing the stop from engaging contact with the end of the stock bar to permit the free fall of the severed end and

to be out of contact with the stock bar before the severance is completed.

60

4. A machine of the class described comprising a chuck to hold the metal stock bar, means for feeding the stock bar through said chuck, a cut-off tool, means for feeding said tool into and away from said stock bar, 65 a stop against which the end of the stock bar is fed, and an operative connection between said stop and said cut-off tool operable, when the cut-off tool is fed into the stock bar, to cause a withdrawing of the stop out of contacting engagement with the stock bar end.

5. In a machine of the class described a chuck to hold the metal stock bar, means whereby said chuck temporarily releases 75 said stock bar, and means for feeding the stock bar through said chuck comprising a roll, means for rotating said roll, and means for bringing the rotating roll into engagement with the stock bar during the interval 80 that it is released by said chuck.

6. In a machine of the class described a chuck to hold the metal stock bar, means whereby said chuck temporarily releases said stock bar, and means for feeding the 85 stock bar through said chuck comprising a pair of pivoted levers arranged on opposite sides of the stock bar, rollers carried by said levers, means for rotating said rollers, and means for moving said levers to bring 90 said rotating rollers into contact with the stock bar during the interval that it is released by said chuck.

7. In a machine of the class described a chuck to hold the metal stock bar, means 95 whereby said chuck temporarily releases said stock bar, and means for feeding said stock bar through said chuck comprising a pair of levers pivoted intermediate their ends on opposite sides of the stock bar, a roller carried by one end of each of said levers, means for rotating said rollers in opposite directions, a carriage mounted to slide in a direction parallel with the direction of movement of said stock bar, link 100 connections between said carriage and said levers, and means for moving said carriage to bring said rollers into contact with said stock bar during the interval that it is released by said chuck.

110

In testimony whereof I affix my signature in presence of two witnesses.

LATHAM H. BRIGHTMAN.
